PILE FABRIC LOOM

Harold V. Hardiman, Thompsonville, Conn., assignor to Bigelow-Sanford Carpet Co., Inc., Thompsonville, Conn., a corporation of Massachusetts

Application February 15, 1937, Serial No. 125,693

14 Claims. (Cl. 139—21)

This invention relates to pile fabric looms and particularly to novel mechanism in such looms for effecting a tight draw of the weft threads around the selvage.

5 In pile fabric looms of the type in which the pile yarns are introduced as warps forming a part of the shed, a problem is presented in that the tension of the shuttle on the weft thread has not been as effective as is desired for drawing the weft 10 tightly about the selvage, which has resulted in objectionable looseness of the pile tufts and backing fabric warps along the selvage and in the formation of unrepresentable loops of weft at the selvage.

15 My experiments have shown that the underlying cause of such looseness and weft loops is that at the time of certain shuttle traverses the pile warps cross the backing fabric warps in the shed at points spaced from the fell, which crossings 20 resist the drawing of the weft toward the fell under the available tension in the shuttle. When the weft shot is beaten up, the warp crossings are moved with the weft to the fell and the excess weft thread extending outside the shed between 25 the crossings and the fell forms itself into a loop protruding from the selvage.

It is the primary object of the present invention to eliminate this condition and I have found that that result may effectively be accomplished by 30 relieving the warps, and particularly the crossings thereof at the time the shuttle tension is acting to draw the weft to the fell. As will appear, I may accomplish this result in a number of ways, such as by deflecting one or more of the sets of warps, 35 forming the shed, toward the fell prior to and during the throw of the shuttle. Alternatively I may release the tension to provide a slack in the warps at such time intervals which also effectively relieves the crossings. In some looms, 40 particularly of the double face type where the problem is extreme because of the remoteness of the crossings from the fell as a result of the pile warps shifting from one face to the other, I prefer, as will appear, to use a combination of both systems.

45 These and further objects and advantages of my invention will appear from a more detailed description thereof in connection with the accompanying drawings, in which:—

Fig. 1 is a perspective view of a double face 50 fabric, indicating a typical condition which my invention remedies;

Fig. 2 is a similar perspective view indicating the 55 mode of operation of my warp engaging member in such double face looms;

Fig. 3 is an enlarged vertical section through the double face fabric of Fig. 2;

Fig. 4 is a plan view of such fabric;

Fig. 5 is a detailed elevation view of certain parts of Fig. 6, and

Fig. 6 is a perspective view of a double face loom with a preferred embodiment of my invention incorporated therein.

In Figs. 1, 2 and 3 I have indicated a double face fabric 1 having an upper backing fabric 2, a lower 10 backing fabric 3 and pile yarns 4 woven therebetween. As customary in weaving fabrics of this type, the upper and lower fabrics are separated by knife mechanism severing the pile yarns 4 intermediate the backing fabrics 2 and 3 to form two 15 individual pile fabrics.

The warp sheds formed when weaving such double face fabrics may vary, but a typical formation may consist, as indicated, of the stuffer warp 5 and binder warps 6a and 6b for the upper fabric 20 shed 11 and similar warps 7, 8a and 8b for the lower fabric shed, crossing between which backing fabric warps are the pile warps 9 all introduced from warp beams or creel spools and formed into sheds by the usual harness mechanism.

In Fig. 1 a weft thread 10 has just been introduced by the shuttle 8 (Fig. 3) entering the shed 11. It will be noted that at this shed the pile warps 9 extend from the lower backing fabric 3 upwardly to cross the backing fabric binder warps 6b of the upper fabric at points 12 which are quite remote from the fell 13 of the cloth.

As a result of these crossings, the tension of the shuttle on the weft has not been effective to draw the weft tightly against the fell 13, as is desired, 35 but the weft movement toward the fell has been impeded by the warp crossings 12, thereby forming a length 15 of weft, outside the shed and between the fell 13 and crossings 12.

As will be understood, the beat-up of the lay 40 follows the introduction of the weft thread 10, and it will be apparent that as the weft is beaten up against the fell, the excess weft 15 will form itself into a protruding loop at the selvage 16 of the upper fabric, previous loops so formed being designated at 20. Such loop formation produces a looseness in the weave at the selvage and also detracts somewhat from the desired trim appearance of the selvage.

In Fig. 2 I have indicated one form of my novel 50 mechanism for overcoming this difficulty, and, as there shown, I provide for the purpose a member 25 secured to a vertical shaft 26 periodically rotated in a manner to be described to assume the position indicated in Fig. 2. The member 25 has

a warp engaging face 28 which, as indicated in Fig. 3, is adapted to abut the pile warps 8 and move them to their dotted line positions indicated at 9'. By such movement of the pile warps the 5 crossings 12, above described, are moved toward the fell, as indicated at 12'.

Referring again to Fig. 2, when the weft thread 10 is now drawn through the shed, the tension in the shuttle will be effective to draw the weft closer 10 to the fell, leaving only a negligible portion 15' of the weft extending outside the shed. The member 25 is retracted immediately prior to the beat-up of the lay, and, in such beat-up, the weft 10 is 15 closely compacted against the fell forming tightly drawn loops 20' rather than the objectionably protruding loops 20, with consequent looseness, as before.

Referring now to Fig. 6 wherein I have illustrated certain parts of a double face loom incorporating a preferred embodiment of my invention, the loom has the usual breast-plate 40 to support the fabric 1 and is provided with harness mechanism 41 for forming warp sheds in the usual manner. The above described member 25 20 is, as stated, secured to one end of the vertical shaft 28, to the other end of which is secured a lever 41 pivoted at 42 to a link 43. The link 43 is pivoted at 44 to an arm 45 loosely journaled at 46 on the shaft 95. The arm 45 carries a 25 cam following roller 51 which is spring pressed against cam 52 by a spring 53 connected at one end to the arm 45 and at the other end to the frame of the machine. Movement of the journal 46 lengthwise of the shaft 95 is prevented by the 30 collars 55. The cam 52 is secured to shaft 50, which is rotated one complete revolution per loom cycle.

A similar condition of weft loopage and looseness is present on the selvage edge 60 (Fig. 4) of the lower fabric 3 and in this case the loops are 40 formed when the shuttle S' (Fig. 3), carrying the weft threads for the lower fabric, enters the shed at the selvage 60.

Accordingly, I provide, in proximity to the 45 selvage edge 60 a warp engaging member 70 identical to the above described member 25, which member 70 is secured to a vertical rod 71 rotated at intervals by mechanism which is the same as that actuating the member 25 and includes the linkage 72, 73 and 74 operated by cam roller 75 engaging cam 76 also secured to the shaft 50.

As indicated, the cams 52 and 76 are shaped to actuate the members 25 and 70 at different 55 times and once each per loom cycle, namely when the followers engage the low portions 52a and 76a of the cams. The proper timing of the actuations of both members relative to the shuttle traverse and the lay beat-up is effected by providing dwells 52a and 76a of proper length and by suitably positioning the cams on the shaft 50 which, as stated, rotates one revolution per loom cycle. Member 25 wips in to deflect the pile warps engaged by it toward the fell immediately 60 prior to the traverse of shuttle S through shed 11 of the upper fabric 2. After the completion of the shot and immediately prior to the beat-up, it is retracted to its position indicated and it does not operate again until after the shuttle S has returned and is again about to enter shed 65 11 from the selvage edge 10. The member 70 operates in similarly timed relation to the entrance of shuttle S' from the selvage 60 into a correspondingly formed shed of the lower fabric 70 75

3 and is similarly retracted prior to the next succeeding beat-up.

As stated above, the problem of weft looseness is most troublesome in double face fabrics for the reason that the cross line 12 is more remote 5 from the fell in weaves of that character due to the shifting of the pile warps from one backing fabric to the other. Although I have found the members 25 and 70 alone to be effective for obviating this difficulty, I prefer to enhance their 10 operation by the provision of mechanism, indicated generally at 80 and 81, which is adapted to release the tension in the pile warps to provide a slack in those warps at the times the members 25 and 70 are functioning. 15

The warp slack devices 80 and 81 are in all respects identical in construction and each has a vertically reciprocating warp engaging member 82 having upper and lower jaws 90 and 91 (Fig. 5) protruding from a hub 92, between which jaws 20 a number of pile warps 8 are threaded. On opposite sides of the member 82 and in horizontal alignment with the lower jaw 91 thereof when the member 82 is elevated, are the warp supporting ledges 83 and 84. The ledges 83 and 84 are 25 formed by bending over strips of metal secured to a boss 86. A clamp 87 secures the slack member to a rod 89 of the loom frame. Vertical reciprocation of the member 82 is effected by a rod 93 secured to hub 92 and passing through a hole drilled in the boss 86. Both rods 93 are pivoted to levers 94 fixed to separate shafts 95 and 96 independently rotatable in the bearing 97. The shaft 95 has an arm 100 carrying a cam follower 101 spring pressed at 102 against cam 103 secured to shaft 50. Similarly the shaft 96 carries fixed to it the lever 105 having cam follower 106 spring pressed by spring 107 against cam 108 which is also secured to the shaft 50. 35

When the loom is threaded with pile warps the 40 selected number of warps on each side which are to be deflected by the members 25 and 70 are passed over the warp supporting ledges 83 and 84 of the slack devices 80 and 81 and between the tongues 90 and 91 of their respective vertically reciprocal member 82. If desired a slight 45 amount of slack may be provided in these selvage warps during such threading by moving both members 82 to their depressed positions indicated for the device 80, during such threading. I have found, however, that if no such slack is 50 provided but the yarn threaded while the warp depressing members of both slackening devices 80 and 81 are elevated, the stretch in the yarn incident to the initial loom operations will soon produce the necessary amount of slack. 55

The shape and position on shaft 50 of the tension releasing operating cams 103 and 108 are so chosen relative to cams 52 and 76 operating the members 25 and 70, as above described, that the member 82 of slackener 80, for example, is moved from its depressed or yarn deflecting position indicated to its elevated position prior to and during the movement of the member 25 from its retracted position to its position in deflecting engagement with the pile warps. The release of tension and the slack thereby provided in the pile warps relieve the tension at the crossings 12 and facilitates the deflecting of the warps by the member 25. When the member 25 is retracted the slackener 80 does not immediately return to its depressed position, but there is a pause before such depression sufficient for beat-up of the lay and shift of the harness to form the next shed. In that manner I insure that the weft 70 75

thread is not moved away from the fell by the takeup of the slack.

The slacker 81 is similarly timed with the member 78.

6 The problem of loose weft selvage is not confined to double face fabrics, but is also present in varying degrees in single face fabrics. Where the pile is high in such fabrics the warp crossings may be quite remote from the fell. Even where 10 the pile is low a problem arises in broad looms because the available tension in the shuttle to draw in the weft is more limited than in narrower looms, for the reason that excessive tension may so retard the shuttle during its long traverse 15 across a broadloom that it will not reach the box at the end of the traverse, with obvious consequences. It is obvious therefore that the mechanisms above described are not limited to use in double face looms.

20 Although I have not illustrated the use of a warp deflector or a warp slack mechanism, such as those described in the double face loom in a single face loom, it will be appreciated that such mechanism can also be employed, in such a loom if desired. Furthermore, in some looms, either 25 single or double face, the warp crossings may be relieved sufficiently to warp slack mechanism alone without a warp deflector.

It will be appreciated that the embodiments of 30 my invention herein disclosed are subject to various modifications without departing from the spirit of my invention, which is to be limited only as indicated in the appended claims. Thus the warp slack mechanism or the warp deflecting 35 members or both may engage all of the pile yarns rather than a limited number adjacent the selvage as herein indicated. Although I have described herein certain movements of those warp yarns which form the pile as effective for the 40 purpose, it is obvious that similar results can be accomplished by moving the binder or stuffer warps or both.

I claim:—

1. In a pile fabric loom, the combination of 45 heddles for forming warp sheds wherein warps form crossings at points remote from the fell, shuttle mechanism for introducing weft shots into the sheds thus formed, a pair of warp deflectors, one disposed adjacent each selvage and 50 each movably mounted in position to enter an opening behind only a limited number of warps leading to a correspondingly limited number of crossings adjacent its respective selvage, and to move said limited number of warps and crossings 55 only toward the fell, and means for alternately actuating the said deflectors in timed relation to the shuttle mechanism to dispose the crossings, so moved, in proximity to the fell when the shuttle, entering the shed at the adjacent selvage, 60 is thrown, whereby to facilitate the draw of the wefts toward the fell by the tension in the shuttles.

2. In a double face fabric loom for weaving 65 juxtaposed backing fabrics connected by pile warps crossing from one backing fabric to the other, the combination of shuttles for the upper and lower fabrics and harness mechanism for shifting pile warps from one backing fabric to the other to form sheds in which pile warps form 70 crossings with backing fabric warps at points remote from the fell, a pair of warp deflectors, one disposed adjacent each side edge of the double fabric and each being independently movable to wipe in between the planes of the upper and lower backing fabrics and to move a limited 75

number only of pile warps and crossings toward the fell, and means for alternately wiping in the deflectors, said means being timed with the shuttle mechanism to dispose the crossings, so moved, in proximity to the fell during predetermined traverses of the shuttles whereby to facilitate the draw of the wefts toward the fell by the tension in the shuttles. 5

3. In a double face fabric loom for weaving upper and lower backing fabrics connected by 10 pile warps crossing from one backing fabric to the other, the combination of harness mechanism for shifting pile warps from one backing fabric to the other to form upper and lower sheds in both of which pile warps form crossings with 15 backing fabric warps remote from the fell, shuttles for the upper and lower fabrics adapted to introduce weft shots into the upper and lower sheds behind said crossings, a pair of warp deflectors, one disposed adjacent each side edge of 20 the double fabric and each being mounted to wipe in behind a limited number only of pile warps leading to a correspondingly limited number of crossings adjacent its respective side edge of the fabric and to move said limited number of 25 warps and crossings only toward the fell, means for wiping in one of the deflectors immediately prior to the throw of the shuttle entering the upper shed from one side of the fabric and means for wiping in the other deflector immediately 30 prior to the throw of the other shuttle entering the lower shed from the opposite side of the fabric, whereby to facilitate the draw of the weft toward the fell by the tension in the shuttle.

4. In a pile fabric loom, the combination of 35 heddles for forming warp sheds wherein warps form crossings at points spaced from the fell, shuttle mechanism for introducing weft shots into the sheds thus formed, a warp deflector movably mounted in position to enter an opening 40 behind warps leading to crossings and to move said warps and crossings toward the fell, warp slackening means positioned to engage warps so moved and operable to produce a slack therein, means for actuating said slackening means, and 45 means for actuating said warp deflector, said several actuating means being timed with relation to each other and to the shuttle mechanism to move slacked warps toward the fell and to dispose the said crossings in proximity to the 50 fell when the shuttle is thrown, whereby to facilitate the draw of the weft toward the fell by the tension in the shuttle.

5. In a pile fabric loom, the combination of 55 heddles for forming warp sheds wherein warps form crossings remote from the fell, shuttle mechanism for introducing weft shots into the sheds thus formed and behind said crossings, a warp deflector movably mounted in position to engage a limited number only of warps leading 60 to a correspondingly limited number of crossings adjacent a selvage and to move said limited number of warps and crossings only toward the fell, warp slackening means positioned to engage said limited number only of warps and operable 65 to produce a slack therein, means for actuating said slackening means and means for actuating said warp deflector, said several actuating means being timed in relation to each other and to the shuttle mechanism to move slacked warps toward 70 the fell and to dispose said crossings in proximity to the fell when the shuttle, entering the shed at said selvage, is thrown, whereby to facilitate the draw of the weft toward the fell by the tension in the shuttle. 75

6. In a pile fabric loom, the combination of heddles for forming warp sheds wherein pile warps form crossings with backing fabric warps remote from the fell, shuttle mechanism for introducing weft shots into the sheds thus formed and behind said crossings, a warp deflector movably mounted adjacent the fell in position to enter an opening behind a limited number only of pile warps leading to a correspondingly limited number of crossings adjacent a selvage and to move said limited number of pile warps and crossings only toward the fell, warp slackening means positioned to engage said limited number only of pile warps and operable to produce a slack therein, means for actuating said slackening means, and means for actuating said warp deflector, said several actuating means being timed with relation to each other and to the shuttle mechanism to move slackened warps toward the fell and to dispose said crossings in proximity to the fell when the shuttle, entering the shed at said selvage, is thrown, whereby to facilitate the draw of the weft toward the fell by the tension in the shuttle.
7. In a pile fabric loom, the combination of heddles for forming warp sheds wherein pile warps form crossings with backing fabric warps at points spaced from the fell, shuttle mechanism for introducing weft shots into the sheds thus formed, warp slackening means positioned to engage pile warps and operable alternately to tension and release the pile warps so engaged to produce a slack therein, warp deflecting means positioned in proximity to the fell of the fabric and movably mounted to move pile warps and crossings toward the fell, and means for actuating said slackening means and said pile warp deflecting means in timed relation with each other and with the shuttle mechanism to provide the said slack and simultaneously to move the said pile warps and crossings toward the fell prior to the completion of predetermined throws of the shuttle whereby to facilitate the draw of the weft toward the fell by the tension in the shuttle.
8. In a pile fabric loom, the combination of a reed, reed beat-up mechanism, harnesses for forming warp sheds in certain of which the warps form crossings remote from the fell, picking mechanism for inserting weft on each beat of the reed, on some of which beats the weft is inserted behind remote crossings, a warp deflector movably mounted to enter from the side of the warps into a warp opening behind a set of warps leading to remote crossings and means for actuating the deflector while the reed is back to advance toward the fell, said set of warps and the crossings to which they lead and to hold said warps and crossings so moved during the insertion of weft behind said crossings so that the picking mechanism draws the weft, so inserted, close to the deflector and to the fell at the side of the fabric before the reed beats up said weft, whereby looping of the weft at the side of the fabric is avoided.
9. In a pile fabric loom, the combination of a reed, reed beat-up mechanism, harnesses for forming warp sheds in certain of which the warps form crossings remote from the fell, picking mechanism for inserting weft on each beat of the reed, on some of which beats the weft is inserted behind remote crossings, a warp deflector pivoted adjacent the fell in position to be swung from the side of the warps into a warp opening behind a set of warps leading to remote crossings and means for actuating the deflector while the reed is
- back to advance, toward the fell, said set of warps and the crossings to which they lead and to hold said warps and crossings so moved during the insertion of weft behind said crossings so that the picking mechanism draws the weft, so inserted, close to the deflector and to the fell at the side of the fabric before the reed beats up said weft, whereby looping of the weft at the side is avoided.
10. In a pile fabric loom, the combination of a reed, reed beat-up mechanism, harnesses for forming warp sheds in certain of which the warps form crossings remote from the fell, picking mechanism for inserting weft on each beat of the reed, on some of which beats the weft is inserted behind remote crossings, a pair of warp deflectors, one disposed adjacent each selvage, and each movably mounted in position to enter a warp opening behind only a limited number of warps leading to a correspondingly limited number of crossings adjacent its respective selvage and to move said limited number of warps and crossings forwardly toward the fell, and means for alternately actuating each of the deflectors at times when the reed is back to advance, toward the fell, its respective limited number of warps and crossings and to hold said warps and crossings so moved during the insertion of the weft from said selvage so that the picking mechanism draws the weft so inserted close to its deflector and to the fell before the reed beats up said weft, whereby looping of the weft at the selvages is avoided.
11. In a pile fabric loom, the combination of a reed, harnesses for forming warp sheds wherein pile warps and backing fabric warps form crossings remote from the fell, mechanism for inserting weft into the sheds thus formed and behind said crossings, pile warp engaging means operable at times to put pile warps under tension and at other times to release the tension on said pile warps to provide slack therein, and means for actuating said pile warp engaging means at the time when the reed is back, and in coordination with the weft inserting mechanism to release the tension on said pile warps so that there is slack therein when the weft is drawn against the crossings during its insertion, whereby, before the reed beats up the weft, the weft may be drawn close to the fell adjacent the selvage by the tension of the weft inserting mechanism.
12. In a pile fabric loom, the combination of a reed, harnesses for forming warp sheds wherein pile warps and backing fabric warps form crossings remote from the fell, mechanism for inserting weft into the sheds thus formed and behind said crossings, means to engage only a limited number of pile warps leading to said crossing adjacent a selvage, said means being operable at times to put said limited number of warps under tension and at other times to release the tension thereon to provide slack therein, and means for actuating said pile warp engaging means at times when the reed is back and in coordination with the weft inserting mechanism to release the tension on said warps so that there is more slack therein than in the warps not so engaged when the weft is drawn against the crossings during its insertion, whereby, before the reed beats up the weft, the weft may be drawn close to the fell adjacent the selvage by the tension of the weft inserting mechanism.
13. In a pile fabric loom the combination of a reed, reed beat-up mechanism, harnesses for forming warp sheds in certain of which pile warps and backing fabric warps form crossings remote from the fell, picking mechanism for in-

serting weft on each beat of the reed, on some of which beats the weft is inserted behind remote crossings, a warp deflector movably mounted to enter from the side of the warps into a warp opening behind a set of pile warps leading to remote crossings, pile warp engaging means operable at times to put said set of pile warps under tension and at other times to release the tension on said set of pile warps to provide slack therein, means for actuating said pile warp engaging means to release the tension on said set of pile warps so that there is slack therein when the reed is back, and means for actuating the deflector to advance, toward the fell, both the pile warps in which the tension is so released and the crossings to which they lead, so that the picking mechanism draws the weft, thereafter inserted, close to the deflector and to the fell at the side of the fabric before the reed beats up said weft, whereby looping of the weft at the side of the fabric is avoided.

14. In a double face fabric loom for weaving upper and lower backing fabrics connected by pile warps crossing from one backing fabric to the other, the combination of a reed, reed beat-up mechanism, harnesses for forming warp sheds for the upper and lower fabrics in which the pile warps form crossings with the upper backing warps remote from the upper fell when the pile

warps cross from the lower to the upper fabric and form other crossings with the lower backing warps remote from the lower fell when the pile warps cross from the upper to the lower fabric, picking mechanism for inserting weft in the upper and lower sheds on each beat of the reed and behind remote crossings successively in the upper and lower sheds, a pair of warp deflectors, one disposed adjacent each side edge of the double fabric and each being mounted to wipe in behind pile warps leading to crossings and to move said warps and crossings forwardly, means for actuating one of the deflectors while the reed is back to advance, toward the upper fell, crossings remote from the upper fell and to hold the crossings so moved while the weft is picked through the upper shed from the side of the fabric adjacent the said deflector and means for actuating the other deflector while the reed is back on the next succeeding beat to advance, toward the lower fell, crossings remote from the lower fell and to hold the crossings so moved while the weft is picked through the lower shed from the side of the fabric adjacent said other deflector so that the picking mechanism draws the wefts so inserted close to the deflectors and to the falls before the reed beats up said wefts whereby looping of the wefts at the selvages is avoided.

HAROLD V. HARDIMAN.
